THOMAS W. PROSSER AND ROY L. MITTELSTAEDT, OF KANKAKEE, ILLINOIS, ASSIGNEES
TO PARAMOUNT TEXTILE MACHINERY CO., OF CHICAGO, ILLINOIS, A CORPOR-
ATION OF ILLINOIS

HOSIERY DRYING FORM

Application filed November 21, 1929. Serial No. 408,879.

This invention relates to hosiery drying forms and, more particularly, to the provision in such forms of a surface or finish which possesses fabric-retaining properties which will prevent hosiery from creeping on the form during the drying operation. Many devices have heretofore been proposed for retaining hosiery properly on a drying form and for keeping the same from creeping during the drying operation. Such devices include fabric engaging clamps of various types and pieces of fabric having an outstanding nap which are secured to the forms and over which the hosiery is drawn. Such devices have, however, not proved entirely successful and particularly in connection with the drying of the very sheer chiffon hosiery which now constitutes so great a part of the hosiery production in this country.

The purpose of our invention is to overcome the disadvantages and defects of the devices heretofore proposed for preventing the creeping of hosiery on drying forms and the particular object thereof is to provide a surface or finish on the form which will function to retain the hosiery securely in place and prevent its creeping on the form as the fabric sets during the drying operation.

Another object of our invention is to provide a surface or finish on a hosiery drying form which will materially increase the heat radiating properties of the form.

A further object of our invention is to provide a hosiery drying form having a friction surface which will engage and hold the fabric of an article of hosiery placed on the form without snagging the fabric.

Other objects of our invention and the advantages attendant thereon will in part be obvious and in part more fully brought out as the description of the invention proceeds.

It will be readily appreciated that an in-

vention of this character is difficult to illustrate. Nevertheless, we have appended hereto drawing illustrating a hosiery drying form provided with a friction surface or finish according to our invention. It will be understood, however, that the drawing is illustrative, merely, and that the invention is not limited to the details of the construction of the form therein disclosed since, obviously, the form is subject to a wide range of modification without departing from the scope of our invention which resides particularly in the surface of the form.

In the drawing:

Fig. 1 is a side elevation of a hosiery drying form embodying a surface or finish in accordance with our invention;

Fig. 2 is a cross section on line 2—2 of Fig. 1 on a considerably enlarged scale and greatly exaggerated for the purpose of more clearly indicating the nature of the surface of the form; and

Fig. 3 is a fragmentary sectional view of a portion of the side of the form, greatly magnified, and showing particularly the character of the surface thereof.

The hosiery drying form illustrated in this drawing may be of any well known construction and comprises sides 1, 1, preferably of steel which are welded or otherwise secured together along the edges 2 and 3. The exterior surface of the sides of the form is indicated by the reference character 4 and it is in this surface that our invention lies.

As will be apparent from an inspection of Fig. 3 of the drawing, the surface 4 of our drying form is roughened throughout, the purpose of which, as heretofore stated, is to provide a means for engaging and frictionally holding the fabric of a stocking on the form so that after the stocking has been pulled down upon the form to the proper length it will not creep up during the drying.

This surface, while it must be sufficiently rough to hold the fabric in place, must not contain sharp projections which would snag the fabric. Thus, the surface 4 is composed of minute projections and depressions which constitute a friction surface well adapted for our purposes, and may be designated a stippled friction surface. This surface may be compared to a half tone engraving, as used in printing, wherein the impression surface is composed of a multitude of microscopic peaks and depressions and known as a stippled surface.

This particular type of surface may be produced in any of a number of ways. For example, it may be etched, or embossed, or abrasive-blasted—subjected to a blast of granular abrasive material such as sand which is projected under high pressure, or produced by rolling under pressure between rolls that have a roughened surface. Furthermore, the surface might be produced by a combination of two or more of these methods, the ultimate object being to provide a surface of the requisite roughness which is well adapted to hold the stocking in place on the form without snagging the fabric. The treatment should not be of such kind as might raise points on the surface as such projections would injure the fabric. The desired frictional character should be produced, as by one of the processes above set forth, to provide a multiplicity of minute pittings or small depressions therein so that the knitted loops of the stocking fabric will cling to the surface. While it might seem that a surface such as described would not have a high frictional characteristic, it has been found that the drying form will satisfactorily hold a stocking against creeping or shrinking if substantially the whole surface thereof which contacts the stocking is treated according to the invention. It is, however, not necessary that the complete surface of the form be treated as described to attain the desired result. Thus, for example, there is little danger of creeping of the fabric on the foot portion of the form because the stocking foot is maintained in proper position due to the curvature of the form in such areas and, hence, a friction surface is not required in this portion.

It will also be readily apparent that a surface of this character, being rough and dull, as compared to the smooth polished surfaces heretofore in use, will materially improve the heat radiating properties of the form and thus improve the drying operation.

A surface such as that described has been found, in actual practice, to accomplish the results heretofore pointed out, namely, the secure retaining of the stocking on the form and the prevention of creeping. As is well known in the art, when stockings are board-

ed they are pulled down upon the form to a certain point and when the fabric dries and sets, the stocking creeps upward on the form so that it is ultimately of less length than it was when originally pulled down on the form. With a form having a surface such as herein described, it has been found that there is practically no creeping of the stocking and hence, longer lengths are obtainable by the use of the forms having a surface in accordance with our invention. That is to say, if a stocking is pulled down on our form to a predetermined point thereon, it will remain substantially at that point during the drying operation and hence it is possible accurately to predetermine the length of the finished stocking. In certain tests conducted, it was found that forms having a surface of our invention produced two and a half times as many stockings of 30½ inch length as were produced on forms having a smooth, polished finish, and more than four times as many stockings of 31 inch length as were produced on the smooth finished, polished forms. The importance of this result will readily be appreciated when the present high cost of silk is considered and when it is realized that the manufacturer is enabled, by the use of forms of our invention, to obtain a little additional length and, in fact, greater length than can be obtained on hosiery drying forms having a smooth finish. As above pointed out, this result could not be obtained by the use of fabric clamps which are apt to injure the delicate fabric of the sheer chiffon hosiery now being manufactured and furthermore such clamps are apt to leave marks on the finished stocking which may render them unfit for the trade.

It is believed that the foregoing description of the finish of our form and the method of producing the same will be entirely clear. By reference to its appearance, it may be stated that the surface which we produce on hosiery drying forms resembles, somewhat, the surface of an egg shell and hence we have designated our forms having this finish as "egg shell" finish forms. It will be understood, of course, that this type of finish is entirely independent of the construction of the form and that our invention is in no way limited to a form of any particular construction. That is to say, our invention is not confined to the surface of a form of sheet metal having sides which are welded together, but may also be embodied in cast metal forms of hard metal which can be successfully sand-blasted and forms of similar materials no matter what may be their particular mode of assembly or construction.

We claim:

1. A hosiery drying form having an exterior surface which over substantially its

entire area is minutely fitted so as to contact and frictionally engage substantially the entire area of a hosiery article placed on the form and prevent the same from creeping during the drying operation.

2. A hosiery drying form having an exterior surface adapted to contact substantially the entire area of a hosiery article placed thereon, the exterior of the form over substantially its entire area having an abrasive-blasted surface adapted to frictionally engage said article and prevent the same from creeping on the form during the drying operation.

15 In testimony whereof, we affix our signatures.

CERTIFICATE OF CORRECTION.

Patent No. 1,907,305.

May 2, 1933.

THOMAS W. PROSSER, ET AL.

It is hereby certified that error appears in the printed specification of the above numbered patent requiring correction as follows: Page 3, line 1, claim 1, for "fitted" read "pitted"; and that the said Letters Patent should be read with this correction therein that the same may conform to the record of the case in the Patent Office.

Signed and sealed this 30th day of May, A. D. 1933.

M. J. Moore.

Acting Commissioner of Patents.
